UNITED STATES PATENT OFFICE.

CHARLES CALLEBAUT AND JULIEN DE BLICQUY, OF LEEDS, ENGLAND.

APPARATUS FOR DYEING OF KNITTED AND WOVEN FABRICS.

Original application filed March 10, 1926, Serial No. 93,667, and in Great Britain November 30, 1925.

Divided and this application filed December 22, 1926. Serial No. 156,433.

The present invention relates to improvements in dyeing machines, and more particularly to the dyeing of knitted or woven articles.

5 The dyeing machines of the present invention include a tank or vat, the contour of the shell of which is constructed with a view to creating a path for the agitated liquor and material over the whole of the internal 10 space of the tank. It has been found by experiment that a tank of circular cross section is unsuitable in that the stream of compressed air and agitated fluid does not follow completely the curvature of the shell, but 15 takes a path of an ellipse having its major axis vertical, the said ellipse covering a portion only of the cross section of the tank. In this way the circulation or agitation current is short circuited i. e. part of the fluid and 20 the material in the tank remains untouched by the stream of fluid created by the compressed air.

It has been found by experiment that the 25 most suitable contour of the shell of the vat or tank is as shown in the accompanying dia- 30 grammatic drawing, which shows a tank in cross section. The length of this is proportional to the desired capacity and has no relation to the height or width of the tank. The 35 basic measurement of the tank is the vertical distance between the points 1, 2. With centre 1 and radius between one and a half times to twice the distance between the points 1 and 2 a curve 3 is described which will form one of the bounding walls of the tank. Similarly the centre 2 and the same radius, (whatever radius that may be between the above stated margin) a curve 4 is described. The curves or quadrants 3 and 4 are joined by the portion 40 or wall 5, which is tangential to both curves 3 and 4. Thus the height of the tank is be- 45 tween four to five times the distance between the basic points 1 and 2, while the wall 5 is equal in length to the distance between the basic points 1 and 2.

With centre 6 and radius between three to 50 four times the vertical distance between the points 1 and 2, the quadrant 7 is described. The point 6 is displaced from the point 1 by an amount equal to the desired radius of the quadrant 7 less the vertical distance between the basic points 1 and 2, and the radius of either of the quadrants 3 or 4. It will be seen that, as the radius of the quadrant 7 55 is between three to four times the distance be-

tween the basic points 1 and 2, while the radii of the quadrants 3 and 4 are between one and a half to twice the distance between the basic points 1 and 2, the radius of the quadrant 7 is between one and a half to two 60 and two thirds times the radius of the quadrants 3 and 4.

In the preferred form of construction the radii of the quadrants 3 and 4 are twice the distance between the base points 1 and 2, while 65 the radius of the quadrant 7 is four times the distance between the said basic points, that is to say, the radius of the quadrant 7 is double that of either of the quadrants 3 or 4, and the height of the tank is five sixths of the width. 70

Portions 8 and 9 of the wheel are then determined, the portion 8 being a vertical continuation of a path tangential to the quadrant 7 and the portion 9 being in a vertical plane at a horizontal distance from the wall 75 8 of between two and a quarter to three and a quarter times the distance between the basic points 1 and 2 or the height of the vertical wall 5. The upper parts of the portions 8 and 9 constitute the loading opening of the vat 80 and it will be noticed that the uppermost part of the section 8 of the shell lies above the horizontal plane tangential with the portion 3 thereby eliminating overflow of fluid within 85 the tank.

One or more inlets for the compressed air are provided at 10, the path of travel of the compressed air being as indicated by the arrow. In this way the liquid and the material within the tank are being lifted while the 90 compressed air is travelling around the portion on the left hand side or circulating curve of the tank shown in the drawings, whilst the material commences to drop after it has reached its uppermost position on the right 95 hand side, i. e. beneath the opening of the tank. The quadrant 7 of the tank is thus termed the dropping curve. In a modified form of construction and in the case where it is desirable to provide two alternate direc- 100 tions of flow of the compressed air, for example, clockwise and anti-clockwise, the dropping curve of the tank is eliminated and a second circulating curve is formed diamet- 105 rically opposite the first, the two curves being separated by an opening of similar width to that disclosed in the above calculations. In tanks of this type it is possible to pass the compressed air into the tank through one or more orifices 10 whereby the material, dye 110

liquor and compressed air will travel clockwise, and after a given period to close such orifice or orifices and open others at a corresponding position at the foot of the second 5 circulating curve so that the material, dye liquor and compressed air will travel anti-clockwise. This method of procedure eliminates the possibility of the material becoming entangled.

10 We declare that what we claim is:—

A tank or vat for dyeing knitted or woven articles having one wall formed by a circulating curve comprising a pair of quadrants and

a vertical joining portion tangential to both quadrants and a second wall conforming to a dropping curve comprising a third quadrant the radius of which is not less than one and a half times the radius of the prior quadrants and joining the lower of said quadrants at the base of the tank or vat.

20 In witness whereof, we have hereunto signed our names this 30th day of November, 1926.

CHARLES CALLEBAUT.
JULIEN DE BLICQUY.
